Des. 198,881
Patented Aug. 11, 1964

198,881

RE-ENTRY VEHICLE OR SIMILAR ARTICLE

Jesse J. King, Dallas, and John H. Boucher, Arlington, Tex., and Cecil V. Carter, Beverly Hills, Calif., assignors, by mesne assignments, to the United States of America as represented by the Secretary of the Air Force

Filed Jan. 8, 1963, Ser. No. 73,094

Term of patent 14 years

(Cl. D71—1)

FIG. 1

FIGURE 1 is a perspective view of the re-entry vehicle or similar article showing our new design;

FIGURE 2 is a vertical projection of the re-entry vehicle or similar article;

FIGURE 3 is a plan view of the re-entry vehicle or similar article; and

FIGURE 4 is a side elevation view of the re-entry vehicle or similar article.

The design is characterized by a somewhat flattened half-ellipsoid fuselage having highly swept wings inclined at a dihedral angle of approximately 45° with the root cord parallel to the plane of symmetry.

The dominant features of the design reside in the portion shown in full lines.

We claim:

The ornamental design for a re-entry vehicle or similar article, as shown and described.
